CLAIM

The ornamental design for a cover for tissue boxes or the like, as shown and described.

DESCRIPTION

FIG. 1 is a top plan view of a cover for tissue boxes or the like incorporating my new design;

FIG. 2 is a side elevational view of FIG. 1;

FIG. 3 is an end elevational view of FIG. 1;

FIG. 4 is a sectional view taken along the line 4—4 in FIG. 1.

FIG. 5 is a sectional view taken along the line 5—5 in FIG. 1.

FIG. 6 is a top plan view of a second embodiment of the design of FIG. 1;

FIG. 7 is a side elevational view of FIG. 6;

FIG. 8 is an end elevational view of FIG. 6;

FIG. 9 is a sectional view taken along the line 9—9 in FIG. 6.

FIG. 10 is a sectional view taken along the line 10—10 of FIG. 6.

FIG. 1.

FIG. 2.

FIG. 3.

FIG. 4.

FIG. 5.

FIG. 7.

FIG. 8.

FIG. 9.

FIG. 10.
